CLAIM

We claim the ornamental design for an input output module for an industrial control system, as shown and described.

DESCRIPTION

FIG. 1 is a first isometric view of an input output module for an industrial control system;

FIG. 2 is a top plan view thereof;

FIG. 3 is a front elevation view thereof;

FIG. 4 is a first end view thereof;

FIG. 5 is a rear elevation view thereof;

FIG. 6 is an opposite end view thereof;

FIG. 7 is a bottom view thereof; and,

FIG. 8 is an environmental isometric view thereof.

Broken lines and unshaded portions entirely encompassed in broken line are not claimed.
